Filed Nov. 13, 1962, Ser. No. 72,475

Term of patent 14 years

(Cl. D58—8)

FIG. 2

FIG. 1

FIG. 3

FIG. 1 is a perspective view of a fitment for packaging containers showing my new design, wherein the outer skirt portion is short.

FIG. 2 is a cross-sectional view of the fitment for packaging containers taken at line 2—2 of FIG. 1.

FIG. 3 is a perspective view of a fitment for packaging containers wherein the outer skirt portion is long.

The dominant features of my design reside in the portions shown in full lines and are characterized by a cylindrical skirt integral with an inner depending skirt which extends horizontally toward the center, forming a narrow shoulder and then tapers downwardly and inwardly, ending in a flat plane extending inwardly all as shown.

I claim:

The ornamental design for a fitment for packaging containers, substantially as shown and described.
